US0D1092588S

(12) **United States Design Patent** (10) Patent No.: **US D1,092,588 S**
(45) Date of Patent: ** Sep. 9, 2025

(54) **INDUSTRIAL ROBOT**

(71) Applicants: **Kuka Robotics Manufacturing China Co., Ltd.**, Shanghai (CN); **KUKA Robotics Guangdong Co., Ltd.**, Foshan (CN)

(72) Inventors: **Sivakumar Thangavelu**, Shanghai (CN); **Shaokun Zhao**, Shanghai (CN)

(**) Term: **15 Years**

(21) Appl. No.: **35/520,834**

(22) Filed: **Feb. 4, 2024**

(80) **Hague Agreement Data**

Int. Filing Date: **Feb. 4, 2024**

Int. Reg. No.: **DM/236724**

Int. Reg. Date: **Feb. 4, 2024**

Int. Reg. Pub. Date: **May 10, 2024**

(51) LOC (15) Cl. **15-99**

(52) U.S. Cl.

USPC **D15/199**

Primary Examiner — Marissa J. Cash

Assistant Examiner — Nicholas J Buffa

(57) **CLAIM**

The ornamental design for an industrial robot as shown and described.

DESCRIPTION

1. Industrial robot

1.1: Front

1.2: Back

1.3: Left

1.4: Right

1.5: Top

1.6: Bottom

1.7: Perspective 1

1.8: Perspective 2

1.9 : Perspective 3

1.10 : Perspective 4

The broken lines and areas enclosed by the broken lines depict portions of the industrial robot and form no part of the claimed design.

1 Claim, 10 Drawing Sheets
